DESIGN FOR A HEAD LAMP FOR AUTOMOBILES

Nellie M. Gage, Dayton, Ohio

Application February 23, 1937, Serial No. 67,816

Term of patent 14 years

To all whom it may concern:

Be it known that I, Nellie M. Gage, a citizen of the United States of America, residing at Dayton, in the county of Montgomery and State of Ohio, have invented a new, original, and ornamental Design for a Head Lamp for Automobiles, of which the following is a specification, reference being had to the accompanying drawing, forming a part thereof.

In the drawing:

Figure 1 is a perspective view of a head lamp having my new design,

Figure 2 is a front elevation of the head lamp, and

Figure 3 is a top plan thereof.

Outstanding features of the design are shown in full lines. The head lamp is adapted to fit across the front of an automobile radiator.

I claim:

The ornamental design for a head lamp for automobiles, as shown and described.

NELLIE M. GAGE,
